(57) **CLAIM**

The ornamental design for a rear bumper for automobile, as shown and described.

DESCRIPTION

FIG. 1 is a front and left perspective view of a rear bumper for automobile, showing our new design;

FIG. 2 is a rear and right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The ghosted or low contrasted portions of the rear bumper for automobile illustrate portions that form no part of the claimed design.

1 Claim, 8 Drawing Sheets
